United States Patent

Des. 238,511

Patented Jan. 20, 1976

238,511

TELEVISION RECEIVER

Melvin H. Boldt, Glenview, Ill., assignor to Zenith
Radio Corporation, Chicago, Ill.

Filed Oct. 2, 1973, Ser. No. 402,875

Term of patent 7 years

Int. Cl. D14—03

U.S. Cl. D56—4 D

Fig. 1.

Fig. 2.

Fig. 3.

Fig. 4.

FIG. 1 is a front, top and left side perspective view of a television receiver showing my new design;

FIG. 2 is a left side elevational view, the right side being a mirror image thereof;

FIG. 3 is a top plan view; and

FIG. 4 is a rear elevational view.

I claim:

The ornamental design for a television receiver, substantially as shown and described.
